Address:
Ervin B. Birney

UNITED STATES PATENT OFFICE.

AUGUSTINE J. CECIL, OF OCONTO, WISCONSIN.

STAKE HOLDER.

Application filed March 26, 1924. Serial No. 701,971.

To all whom it may concern:

Be it known that I, AUGUSTINE J. CECIL, a citizen of the United States, and resident of Oconto, in the county of Oconto and 5 State of Wisconsin, have invented certain new and useful Improvements in Stake Holders; and I do hereby declare that the following is a full, clear, and exact description thereof.

10 This invention relates to stake holders. It has been the customary practice to provide stake holders in the form of non-removable sockets on flat cars and similar devices and to seat the lower end of the 15 stakes in such sockets. These stakes were difficult to remove without endangering the operator, as the material held by such stakes would then move and damage the operator, as, for example, when logs were being 20 transported. In addition to this, the stakes frequently broke off in the sockets and difficulty was found in replacing them.

This invention is designed to overcome the above defects and objects of such invention are to provide a stake holder, which 25 has a movable portion, adapted to permit the ready removal of the stake, which is so constructed that the movable portion may be securely locked in closed position, which 30 is adapted to be operated by means of a hook or other elongated member, so as to avoid any possibility of damage to the operator.

An embodiment of the invention is shown 35 in the accompanying drawing, in which:

Figure 1, is a side elevation of the stake holder, showing the stake in position.

Figure 2, is a plan view partly in section of the structure, shown in Figure 1, with 40 the stake removed.

Figure 3, is a sectional view on the line 3—3 of Figure 1.

Figure 4, is a sectional view on a line 4—4 of Figure 2.

45 The stake holder comprises a body portion 1, which is adapted to be bolted, as illustrated in Figure 1, to the side 2 of a car. This body portion is provided with a pair of spaced outwardly extending flanges 3, which define a channel between them.

50 The body portion is provided on opposite sides of this channel with outwardly projecting lugs 4. These lugs 4 are provided with slots 5, extending inwardly from

their outer sides and the slots are so formed that an inwardly projecting ledge 6 is provided, for a purpose hereinafter to appear. The lugs are further provided with outwardly projecting apertured ears 7. 60

The movable member 8 is of U-shape and encloses the flanges 3, 3. This movable member is pivoted to the flanges, adjacent its lower end, by means of a pintle pin 9, and is preferably cut away adjacent said lower portion, as shown in Figures 1, 3 and 4. The member 8 is provided with laterally projecting ears 10, which are adapted to contact with the body portion 1 of the stationary member, when such member is swung upwardly into closed position. 70

A pair of jointed latch members 11 are pivotally mounted at their lower ends, as by means of bolts 12, to the body portion 1. These members are provided with hinge portion 13, adjacent their lower ends and are provided with outwardly projecting manipulating pins 14, adjacent their upper ends. 75

When it is desired to lock the member 8 in 80 its closed position, it is rocked into such position and the latches 11, are swung upwardly about their pivots 12, until their upper ends pass into their slots 5, in the lugs 4. By having the lip 6, formed in said slots, the friction between the latches 11 and the lugs, is materially reduced. After the latches have been moved into lug engaging position, slotted pins 15, are dropped through the apertured ears 7 of the lugs 4, and are positioned 85 upon the outer sides of the pins 14 of the latches, thus retaining the latches in closed position. If desired, the pins 15 may be attached to either the body or the movable portion, by means of chains, not shown. 90

When it is desired to release the stakes 16, the operator removes the pins 15, thereafter, he employs any suitable type of tool and engages the pins 14 with said tool. He then draws outwardly, thus rocking the 100 latches outwardly, until their upper ends disengage the lugs 4. Thereafter, the stakes 16 may rock outwardly, thus rocking the member 8 outwardly. During this motion, the latches 11, rock at their hinge joints 105 13 and permit the member 8 to rock outwardly, thus releasing the stake.

It will be seen that a stake holder has been provided, which may be readily opened, which is of sturdy and substantial 110

construction and which may be operated from a distance, thus guarding against accidents.

Although the invention has been described in considerable detail, it is to be understood that the invention may be variously embodied and is, therefore, to be limited only as claimed.

I claim:

10. 1. A stake holder comprising a body member, having outwardly projecting spaced flanges, a U-shaped movable member adapted to enclose said flanges and pivoted adjacent its lower end to said flanges, said movable member having outwardly projecting ears, and latches engaging said ears and locking said movable member in closed position.
20. 2. A stake holder comprising a body member having outwardly projecting spaced flanges, slotted lugs extending outwardly from the upper portion of said body member, a movable U-shaped member enclosing said flanges and pivoted adjacent its lower end to said flanges, said movable member having outwardly projecting ears;

and a pair of latches pivoted adjacent their lower ends to said body member and adapted to have their upper ends positioned within said slotted lugs, said latches being jointed adjacent their pivoted ends. 30

3. A stake holder comprising a body member having outwardly projecting spaced flanges, slotted lugs extending outwardly from the upper portion of said body member; a movable U-shaped member enclosing said flanges and pivoted adjacent its lower end to said flanges, said movable member having outwardly projecting ears, a pair of latches pivoted adjacent their lower ends to said body member and adapted to have their upper ends positioned within said slotted lugs, said latches being jointed adjacent their pivoted ends, and 40 means for retaining said upper ends of said latches within said lugs. 45

In testimony that I claim the foregoing I have hereunto set my hand at Oconto, in the county of Oconto and State of Wisconsin.

AUGUSTINE J. CECIL.
